REPLACEABLE PLOW SHARE POINT

Ralph C. Frevik, Detroit, Mich., assignor, by mesne assignments, to Ford Motor Company, Dearborn, Mich., a corporation of Delaware

Application November 15, 1949, Serial No. 127,403

1 Claim. (Cl. 97—125)

1

This invention relates to an improved replaceable plow point for moldboard plows.

Heretofore, there have been a large number of constructions of replaceable plow points proposed, but no prior constructions have met with any substantial degree of success, primarily because such points were either not adequately supported and secured on the plow, or the cost of the replaceable point so nearly approached the cost of the more conventional integral share and point that the farmer did not realize any substantial economic advantage in purchasing the replaceable points.

In accordance with this invention, the manufacturing cost of a replaceable point for a moldboard plow is substantially reduced due to the virtual elimination of the gunnel portion of the replaceable point, i. e., that portion of the point which defines the landside face of the plow point and generally projects rearwardly a substantial distance from the extreme forward end of the plow point. Heretofore, such gunnel portion has generally been considered necessary to adequately support the cutting end of the plow point and, accordingly, has been formed with relatively massive dimensions, thereby forming a substantial portion of the total cost of the replaceable point. However, in actual use, such gunnel portion is subjected to little wear compared to the cutting face of the plow point, so that when a farmer discarded a plow point because of wear of the cutting surfaces, he was discarding the relatively unimpaired gunnel portion as well.

As indicated above, a replaceable plow point embodying this invention substantially eliminates such gunnel portion and the forward end of the landside of the plow is extended to underlie a substantial portion of the replaceable plow point and perform the supporting functions of the eliminated gunnel portion. Hence, in effect, substantially all of the material entering into a replaceable plow point embodying this invention forms part of the wearing surfaces of the plow point and when a worn plow point is replaced, the farmer is not discarding a relatively unused gunnel portion.

Still another feature of this invention is the provision of an improved arrangement for effecting the rigid securement of a replacement plow point to a moldboard plow. A plurality of surfaces on the plow point are caused to interlock with cooperating surfaces on the landside, the frog and the moldboard so that the plow point

2

is securely locked in assembly by a minimum number of bolts.

Accordingly, it is an object of this invention to provide an improved plow point construction for a moldboard plow which can be securely mounted and supported on the plow and yet be conveniently replaceable when worn.

Another object of this invention is to provide unusually economical replaceable plow point constructions for a moldboard plow characterized by the substantial elimination of the gunnel portion of the plow point and the utilization of a forward extension of the plow landside to perform the supporting functions of the eliminated gunnel portion.

The specific nature of this invention, as well as other objects and advantages thereof, will become apparent to those skilled in the art from the following detailed description, taken in conjunction with the attached sheets of drawings on which, by way of preferred example only, are illustrated various modifications of this invention.

On the drawings:

Figure 1 is a side elevational view of a moldboard plow from the landside side, showing a replaceable point secured to the plow in accordance with one modification of this invention.

Figure 2 is a plan view of the forward end of the plow shown in Figure 1 with the moldboard removed.

Figure 3 is an elevational view showing a modified manner of securing the plow point to the extended landside wherein a dovetailed joint is utilized.

Figure 4 is a plan view of Figure 3.

Figure 5 is a cross sectional view taken along the plane 5—5 of Figure 3.

Figure 6 is a plan view of the forward end of a plow showing still another modification of this invention wherein the replaceable plow point is supported by an extended portion of the frog and the landside.

Figure 7 is a side elevational view of Figure 6.

Figure 8 is a sectional view taken along the plane 8—8 of Figure 6.

Figure 9 illustrates a further modification of this invention and is a side elevation view of the front end of a plow.

Figure 10 is a cross sectional view taken along the plane 10—10 of Figure 9.

Figure 11 is a cross sectional view taken along the plane 11—11 of Figure 1.

Figure 12 is a fragmentary plan view of Figure 9.

As shown on the drawings:

Briefly, this invention comprises a replaceable plow point having an exterior contour shaped to blend with the contour of the share and the moldboard. The landside is provided with an extended tapered point which is recessed in an interior pocket formed on the replaceable point and such point is removably secured to such extended landside portion. The frog is also extended and such extension cooperates with a recess in the replaceable plow point whereby such point is also mounted on the frog. The share is arranged in abutting relationship with the replaceable point so that in cooperation with the landside, the replaceable point is locked against rocking movement and is thus rigidly secured to the plow.

There is shown in Figure 1 a plow construction comprising a moldboard 15 of conventional configuration secured to a frog 16 and beam 18 by a pair of bolts 17. A share 18 is secured to frog 16 below moldboard 15 by a pair of screws 19. Share 18 is of conventional construction but is without the usual share point, thereby shortening such share and the end thereof is squared off as shown at 20 in Figure 2.

Frog 16 is provided with a forwardly projecting, tapering end portion 21 on which is mounted a replaceable plow point 22. Plow point 22 has an exterior configuration substantially conforming to the shape of the conventional integral share point. Point 22, however, is provided with a rearwardly opening recess 23 so that such point may be snugly slipped over the projecting end portion 21 of frog 16. Recess 23 also opens downwardly, as best shown in Figure 11. Point 22 is provided with a squared end surface 24 which abuts the end surface 20 of share 18. A second recess 25, which communicates with recess 23, is provided on the landside face of point 22 for a purpose to be presently described.

A landside member 26 is secured to frog 16 on the side opposite moldboard 15 by a pair of screws 27. Landside 26 is provided with a tapered front end portion 28 as shown in Figure 1. The recess 25 in the landside face of plow point 22 is shaped to snugly receive the tapered end portion 28 of landside 26. The upper top surface 29 of the landside 26 abuts a shoulder 30 defined by recess 25. A transverse screw 31 inserted in a suitable hole in the forward end of the end portion 28 of landside 26 engages a threaded hole 32 in point 22 to secure point 22 to the tapered end portion of landside 26. Also, a screw 33 is provided to secure point 22 to frog 16 as shown in Figure 2. Thus, it is readily apparent that the abutment of the upper surface 29 of the tapered end portion of landside 26 with shoulder 30 in point 22 and the abutment of the end of share 18 with point 22 substantially eliminates any possibility of rocking of point 22 when mounted on the plow. Screws 31 and 33 permit rapid and convenient disassembly of the point 22 from the plow to permit replacement thereof when such point is worn beyond use.

In Figures 3, 4 and 5, there is illustrated a modification of the replaceable point shown in Figures 1 and 2 wherein a tapered dovetail is provided on the landside which engages a corresponding dovetailed slot provided in the replaceable point. The elements of the plow shown in Figure 2 correspond to those shown in Figures 1 and 2; however, in this instance, the landside 26 of this modification is provided at its forward end with a wedge-shaped point 34 having dovetail or beveled edges, as best shown at 35 in Fig-

ure 5. A dovetailed slot 36, which communicates with the frog receiving recess 23, is provided in the landside face of point 22 and corresponds in shape to the dovetailed end 34 of landside 26. A screw 37 in the forward end of wedge-shaped point 34 secures point 22 to landside 26. As in the arrangement shown in Figures 1 and 2, the landside and share in this construction rigidly supports the point 22 against rocking or other displacement.

A further modification of a replaceable plow point embodying this invention is shown in Figures 6, 7 and 8. In such modification, the frog 38 is provided with an extended substantially wedge-shaped toe portion 39. A shortened share 40 is secured to frog 38 by a plurality of screws 41 and such share has a squared front end surface 42 which abuts a corresponding rear surface 43a on replaceable plow point 43. Plow point 43 is provided with a wedge-shaped recess 44 corresponding in shape and size to toe portion 39 of frog 38 for mounting the point on such toe portion. In contrast to the other modifications of this invention, recess 44 has a bottom wall 44a (Figure 8). The plow point 43 is assembled to toe portion 39 by sliding such point over the toe portion 39 and tapping the end of the point as with a hammer, whereby such toe portion is tightly wedged in recess 44. A bolt 45 secures point 43 to frog 38 as shown in Figure 8. The landside face of point 43 is recessed as shown at 46 in Figures 6 and 7 to receive a slightly reduced end portion 47 of a landside 48. Landside 48 is secured to frog 38 by screws 49. The tapered end portion 47 of landside 48 snugly fits within the recess 46 provided in point 43. The upper surface 51 of end portion 47 abuts a shoulder 52 defined by recessed surface 46 to additionally support point 43. The abutment of share 40 with point 43 completes the locking arrangement thus effectively preventing rotation of the point.

In the modification shown in Figures 9 and 10, the landside 53 is provided with a forwardly extending end portion 54 of L-shaped configuration, as best shown in Figure 10. A replaceable point 55 is provided which is mountable on a frog 56, in much the same manner as described in the modifications shown in Figures 1 and 2, and placed adjacent a share (not shown) and a moldboard 57. In this modification, however, the landside surface of point 55 is recessed and the bottom surface of point 55 is also recessed to receive the L-shaped end 54 of the landside 53 in order that the point 55 will be flush with the landside on both the side and bottom of the front portion 54 thereof. A screw 58 vertically disposed in the bottom portion of the L-shaped end 54 of the landside fastens point 55 to such extended end portion 54. Three screws 60 secure landside 53 to frog 56. As in the previously described modifications, the upper surface of the forward landside portion 54 abuts the shoulder defined by the recessed surface 61 in point 55 to securely lock point 55 against rotation.

From the foregoing description, it is clearly apparent that there is here provided a replaceable plow point for a plow which may be readily and conveniently assembled to a plow of the moldboard type and, when assembled, is positively locked against the various forces acting on the point in plowing by the cooperating abutment of surfaces of the landside and share with the point.

It will, of course, be understood that many details of construction may be varied through a wide range without departing from the principles

of this invention and it is, therefore, not the purpose to limit the patent granted hereon otherwise than necessitated by the scope of the appended claim.

I claim:

In a plow the combination of a frog provided with angularly disposed moldboard and landside surfaces, a landside, means for mounting said landside on said landside surface of said frog, said landside having a tip portion extending forwardly beyond said frog, said tip portion having an L-shaped vertical cross-section, a share wing, means for securing said share wing to the moldboard surface of said frog with its forward edge disposed rearwardly of the forward end of said frog, a replaceable share point having a recess for receiving the forward edge of said frog, said share point having a rearward edge surface, means for securing said point to said frog with its rearward edge surface in abutment with the forward edge of said share wing, said share point having recesses respectively on its landside face

and its adjacent bottom face constructed and arranged to receive said L-shaped extending tip portion of said landside in flush relationship therein, thereby rigidly supporting said plow point, and bolt means traversing each face of said L-shaped extended tip portion for removably securing said share point to said extended tip portion.
